UNITED STATES PATENT OFFICE.

WALTER H. KANEN, OF OAKLAND, CALIFORNIA, ASSIGNOR OF ONE-HALF TO MARTIN L. MCKEAN, OF OAKLAND, CALIFORNIA.

LIFE-PRESERVER.

1,123,194.

Specification of Letters Patent. Patented Dec. 29, 1914.

Application filed February 24, 1914. Serial No. 820,478.

To all whom it may concern:

Be it known that I, WALTER H. KANEN, a citizen of the United States, residing at Oakland, in the county of Alameda and State of California, have invented certain new and useful Improvements in Life-Preservers, of which the following is a specification.

This invention relates to improvements in life preservers and particularly to the collapsible type, which may be worn under the clothes and inflated when required.

The principal object of my invention is the construction of an improved device of the character named, which will occupy a very small space, which may be formed into the regular garments and thus be worn concealed on the person.

Another object is to provide an improved form of valve used in connection therewith.

With these and other objects in view my invention consists in the new and novel construction and arrangement of parts as herein described and pointed out in the appended claims.

Reference is to be had to the drawings forming a part of this specification wherein,

Figure 1 is a view in perspective of my improved device mounted on a person. Fig. 2 is a view in perspective of the device placed in and forming a part of a man's vest. Fig. 3 is a detail view in elevation of one end of the device removed from the garment. Fig. 4 is an enlarged sectional view on 4-4, Fig. 2. Fig. 5 is an enlarged sectional view of the valve used with my device.

Referring to corresponding parts by the same numerals of reference, 1 denotes the buoyant element of the device and the same consists of a plurality of impervious airtight elastic tubes 2, having their ends closed. These tubes are surrounded by a jacket 4 of strong inelastic material which prevents tube 2 from expanding too greatly while being inflated.

Jackets 4 project beyond the ends of the air tube and have their ends fastened to flat connecting strips 5, and to one of these strips is attached a buckle 6 and to the other a strap 7. Each tube 2 is provided with an inflation tube 8 the two being joined in a single tube 9 provided with a valve 10. The latter is strongly attached to tube 9 in any

preferred manner, and provided with the axial passages 11' and 12 connected by the 55 conical seat 13. Adapted to fit this seat is a conical valve 14, which is held adjacent the seat by a cross pin 15. A cap 16 is provided which may be placed in threaded engagement with the valve body and the gasket 17 60 thus brought into intimate contact with the valve end to make a perfectly air tight union. A string 18 is connected to eyes 19 and 20 in the valve and cap respectively, to prevent the latter from becoming lost, and 65 annular ribs 21 so are formed on the outside of the valve body to make the device easy to hold between the lips when inflating.

In practice I prefer to place the buoyant tubes within a garment between the outside 70 and lining thereof, as shown in Fig. 4, the same being positioned by rows of stitching 11. The strips 5 are positioned adjacent the edge seams of the garment and the buckle and straps brought out through suitable 75 slits in the lining. Tube 9 is coiled or other disposed upon the inside of the garment so held that it may be quickly reached and pulled out for inflation purposes.

Having thus described my invention it 80 will of course be understood that various modifications may be made in detail and form without departing from the spirit thereof.

What I claim and wish to cover by Letters Patent is:—

1. The combination in a device of the character named of a plurality of elastic air tight tubes, a flexible inelastic covering for each of said tubes, the adjacent ends of said 90 coverings extending beyond the ends of said tubes, flat metallic strips, connecting adjacent ends of said flexible covering, said tubes, covers and strips being placed between a garment and the lining thereof, 95 rows of stitching adapted to hold said tubes positioned in said garment, means for attaching said strips together and means for inflating said tubes.

2. In a device of the character named 100 comprising the combination with a garment for the upper part of the body, of a plurality of elastic airtight tubes, and inelastic flexible coverings therefor, said coverings projecting beyond the ends of said tubes, 105 flat strips connecting adjacent ends of said

flexible coverings, said tubes, coverings and connecting strips being held between said garment and the lining therefor, rows of stitching preventing movement of said parts within said garment, relatively small flexible tubes communicating with said air tight tubes, said small tubes being joined into a larger tube, said last mentioned tube carry-

ing a valve adapted to retain the air pressure within said air tight tubes.

In testimony whereof I affix my signature in presence of two witnesses.

WALTER H. KANEN.
